Primary Examiner — Sandra Snapp*Assistant Examiner* — Caitlin Mackenzie Williams(74) Attorney, Agent, or Firm — Cowan, Liebowitz & Latman, P.C.(57) CLAIM

The ornamental design for a casual footwear as shown.

DESCRIPTION

FIG. 1 is a top view of a casual footwear of the present invention;

FIG. 2 is a bottom view thereof;

FIG. 3 is a left side view thereof;

FIG. 4 is a right side view thereof;

FIG. 5 is a front view thereof;

FIG. 6 is a rear view thereof; and,

FIG. 7 is another front view showing a portion thereof in an unbuttoned configuration.

The broken lines in the drawings, including broken lines that represent stitching, illustrate features of the casual footwear that form no part of the claimed design.

1 Claim, 7 Drawing Sheets(56)
